REFRIGERATED MERCHANTISING CASE FOR DISPENSING FROZEN FOOD

Christian K. Nelson, Henrico County, Va., assignor to Eskimo Pie Corporation, Richmond, Va., a corporation of Delaware

Filed Sept. 28, 1959, Ser. No. 57,712

Term of patent 14 years

(Cl. D80—11)

Figure 1 is a front perspective view taken from the top and one side of a refrigerated merchandising case for dispensing frozen food embodying my new design, the opposite side being substantially the same; and

I claim:

The ornamental design for a refrigerated merchandising case for dispensing frozen food, as shown and described.
